UNITED STATES PATENT OFFICE

165,650

AUTOMATIC PERFUME DISPENSER

Larry Hoffman, Toronto, Ontario, Canada, assignor to Perfumatic of Canada Limited, Toronto, Ontario, Canada

Application May 10, 1951, Serial No. 15,126

Term of patent 14 years

(Cl. D52—3)

To all whom it may concern:

Be it known that I, Larry Hoffman, a citizen of Canada residing in the city of Toronto, in the county of York, Province of Ontario, and Dominion of Canada, have invented a new, original, and ornamental Design for Automatic Perfume Dispenser, of which the following is a specification, reference being had to the accompanying drawing, forming part thereof, wherein

Fig. 1 is a perspective view of an automatic perfume dispenser, showing my new design.

Fig. 2 is a side elevation showing the side opposite to that seen in Figure 1.

Fig. 3 is a front elevation thereof.

I claim:

The ornamental design for an automatic perfume dispenser, as shown.

LARRY HOFFMAN.
